CAN OPENER

Edward L. Verhagen, Rahway, N. J., assignor to
 The Regina Corporation, Rahway, N. J., a corporation of New York

Application November 24, 1950, Serial No. 197,411

3 Claims. (Cl. 39—9)

1

The invention relates to a can opener and more particularly to that type of can opener which utilizes a rotary cutting disc and a rotating feeding device for engaging the flange of the container and by means of which the container is propelled during engagement with the cutting disc. Can openers of this type are adapted to remove the top of the container by severing the top at a point adjacent to its periphery.

More particularly, the invention relates to a novel construction of such can opener in which there is provided a spring guide for effecting the proper positioning of the top flange of the can in relation to the rotary cutting disc and for maintaining the container in the proper position for severing the top of the container as the container is rotated by the feeding device.

An object of the invention is to provide a spring guide which properly positions the container to be opened in relation to the rotary cutting disc and the rotating feeding device when the container is loaded in the can opener, i. e., when the container is applied to the device to effect the operation of opening the container. The guide means insures insertion of the container into the can opener with the top of the can perfectly horizontal and properly centered under the cutting disc and between the feeding device and the cutting disc.

A further object of the invention is to provide such a spring guide which is effective to hold the container in proper location with respect to the cutting disc while the top of the container is being punctured to start the severing of such container top.

Another object of the invention is to provide such a spring guide which will exert a proper guiding pressure on the container irrespective of the wall thickness of the container, or the thickness or height of the bead or flange located at the top peripheral edge of the can.

A still further object of the invention is to provide a spring guide foot which will position the side wall of the container away from the feeding device, and will thus prevent the tearing off and shredding of any paper wrapper on the container. A common defect of can openers of the type here under consideration, heretofore in use, has been the jamming of the feed mechanism by an accumulation of small shreds of paper torn from the paper wrapper of the container. By positioning the container being operated on by the device, at a slight angle slanting away from the feeding device, the tearing and shredding of the paper wrapper is effectively prevented, and the jamming

2

due to the accumulation of such shredded or torn pieces is eliminated.

A still further object of the invention is to provide a spring guide of such shape and configuration that it includes two front contact portions spaced at the same distance from the face of the rotating feeding device, which contact points exert sufficient pressure when the container revolves, to compensate for the natural tendency of the container to work sideways and away from the proper cutting position. The shape and configuration of the spring guide is also such that it is effective to press the container outwardly against the cutting disc and thereby insure the cutting of the container top close to the inside wall of the container, as when making the original puncture.

It is another object of the present invention to provide a spring guide member which will act to support the can during cutting in such a manner as to prevent sidewise tipping. The feed mechanism in can openers of the type here being considered usually consists of a single toothed wheel. Such wheel acts to support the can at only one point, and therefore can not prevent tipping of the can about that point. A spring guide embodying the present invention provides portions which engage the underside of the bead on the can on both sides of the feed wheel, thus effectively preventing tipping.

Further and other objects of the invention will appear to those skilled in the art from the following description of a specific embodiment of my invention and as illustrated in the accompanying drawings, in which drawings:

Fig. 1 is a reduced partially broken away plan view of a can opener constructed in accordance with the present invention, showing the same with a container to be opened applied thereto;

Fig. 2 is an enlarged side view thereof;

Fig. 3 is an enlarged front view thereof without the container applied thereto;

Fig. 4 is a still further enlarged plan view of the spring guide member;

Fig. 5 is a front view thereof; and

Fig. 6 is a side view thereof.

Referring more particularly to the drawings, in which similar reference characters identify similar parts in the several views, the can opener is constructed for mounting on a wall or other vertical support by means of a mounting bracket 10 which is shown partly broken away. At the outer end of the mounting bracket, and extending at right angles thereto is the housing 11 (shown broken away in all views). The housing is a

hollow and has opening 12 therein. Within the opening 12 is a sleeve 13 mounted on the housing 11 by means of pin 14. The pin 14 permits the sleeve 13 to rock relative to the housing 13 permitting the cutting disc 15 to move relative to the toothed drive wheel 16.

Mounted for axial sliding movement within the sleeve 13 is the cutting disc shaft 17. The shaft 17 is keyed to the sleeve 13 and therefore while it is free for limited movement axially of the sleeve 13, it cannot rotate relative to the sleeve 13. Rigidly secured to the sleeve 13 is the extension member 18. The extension member 18 has a cam face 19.

A second sleeve 20 having cam face 21 is mounted on shaft 17. The sleeve 20 is free to rotate about the shaft 17, but is held against axial movement relative to the shaft 17. The forward point of the cam face 21 on sleeve 20 abuts against the cam face 19 on extension 18 of sleeve 13, and the rearward end of the sleeve 20 abuts against the washer 22 which is held securely on the shaft 17 by bolt 23. A handle 24 is rigidly secured to the sleeve 20 and the sleeve 20 is rotated by this handle 24.

As the sleeve 20 is rotated by handle 24 the forward point of the cam face 21 rides on cam face 19 of the extension 18. The sleeve 20 is thus moved relative to the sleeve 13 and carries with it the shaft 17. A spring not shown urges the sleeve forwardly so that the forward point of cam face 21 is constantly pressed against cam face 19. The cam faces 19 and 21 are formed so as to permit the cutting disc 15 to move from an open position a small distance away from the drive wheel 16 to a closed position abutting the drive wheel 16.

The stop member 25 is secured to the sleeve 20 so as to act as an eccentric. As the sleeve 20 is rotated by the handle 24 the stop member 25 bears against the stop plate 26. The stop plate is urged upwardly by a spring 26b so that it is constantly pressed against the stop member 25, and the stop member 25 is provided with a lug 25a which prevents further rotation of the sleeve 20 when it engages the raised portion 26a of the stop plate 26.

Due to its eccentric mounting on the sleeve 20, as the stop member 25 rotates it pivots the sleeve 13 about pin 14, the sleeve 13 carries with it the shaft 17, raising the rearward end of the shaft 17 and swinging the cutting disc 15 downward toward the drive wheel 16. Rotation of the handle from the dotted position shown in Fig. 1 to the solid position moves the cutting disc 15 rearwardly and swings it downwardly.

The drive wheel 16 is secured to shaft 21. The shaft 21 is mounted for rotation in the housing 11 and a crank 28 is provided so that it can be manually rotated. A coil spring 29 is mounted within recess 30 of the housing 11 and will yield to pressure of the drive wheel 16 when the container is pressed against the wheel and thus the opener is adapted to receive containers having flanges and walls of different thicknesses and will insure effective gripping and feeding during the entire cutting operation although there may be slight variations in the dimensions of the can. This is also a function of the spring guide member 31 as will be explained later.

The flat spring guide member 31 is of the configuration shown in Figs. 4 through 6, and is provided with an aperture 32 so that it may be mounted on shaft 21. The spring guide member

31 is located on the shaft 21 between the drive wheel 16 and the coil spring 29.

The guide member 31 is formed with two projecting wings 33 and 34, each wing being spaced equally from the center of the guide member 31. Each wing is V-shaped in the side view as can be seen clearest in Fig. 6. The wing 33 has an upper portion 35 which slants upwardly and inwardly from the outermost point 36 and a lower portion 37 which slants downwardly and inwardly from the outermost point 36. Similarly the wing 34 has an upper portion 38 which slants upwardly and inwardly from the outermost point 39 and a lower portion 40 which slants downwardly and inwardly from the outermost point 39.

The wings 33 and 34 are each bent back as shown to present a rounded surface to the container and to provide wings of substantial strength. The outermost points 36 and 39 on the wings 33 and 34, respectively, are equidistant above the bottom of the guide member 31 and the surfaces presented by the portions 35 and 37 are respectively parallel to the surfaces presented by the portions 38 and 40.

The portions 35 and 38 act to support the container during the cutting operations and cooperate with the pin 41 and the projecting lug 42 on the face of the cutter to originally, properly position the container vertically relative to the cutting disc 15 and the toothed drive wheel 16. The wings 33 and 34 engage the side of the can and properly position it horizontally.

The wing 34 is higher than the wing 33, and has a longer connecting portion with the rest of the guide member 31 and therefore is stronger than the wing 33. Thus the wing 34 exerts a greater force on the container being operated on, and acts to overcome the natural tendency of the container to move to the right in Fig. 3 as the top is being cut.

The lower portion of the guide member 31 is formed with a channel shaped portion 43 which grips tightly the projection 44. This holds the guide member 31 against rotation about the shaft 17 and makes certain that the guide member 31 will remain in the proper position. A protrusion 45 in the channel shaped portion 43 extends outwardly a small distance beyond the outer surface of the drive wheel 16 and bears against the side wall of the container being operated on. This tips the container slightly and positions the side wall of the container away from the drive wheel 16, preventing any tearing or shredding of a paper wrapper on the container as it revolves. Such torn or shredded paper has a tendency to clog the drive wheel retarding and eventually preventing its rotation.

In operation a container is positioned under the cutting disc 15 with the flange resting on the top of the drive wheel 16 and on portions 35 and 38 of wings 33 and 34. Guiding the can into the proper position are pin 41, lug 42 and wings 33 and 34 of the guide member 31. The handle 24 is then rotated from the dotted position shown in Fig. 1 to the solid position placing the cutting disc 15 into the position shown in Fig. 2. This movement of the cutting disc punctures the container top. Rotation of the handle 28 rotates drive wheel 16 which in turn rotates the container. Portions 35 and 38 of wings 33 and 34, respectively, aid in supporting the container during this cutting action.

I claim:

1. A can opener comprising a cutting element, a container feeding means, and guide means, for

positioning the container in the can opener, said guide means comprising a flat metal spring guide member, having lateral forwardly extending wing portions on both sides of said feeding means, each of said wing portions having an outermost point and extending upwardly and inwardly from said outermost point thereby presenting an inclined surface to receive the flange of the container being operated on by said can opener, said can opener including a housing and a projection in said casing beneath said feed means, said guide member having a lower channel shaped portion adapted to fit over said projection, and a protrusion on said channel shaped portion, extending outwardly beyond the outermost point of said feeding means.

2. A can opener comprising a cutting element, a container feeding means, and guide means, for positioning the container in the can opener, said guide means comprising a flat metal spring guide member, having lateral forwardly extending wing portions on both sides of said feeding means, each of said wing portions having an outermost point and extending upwardly and inwardly from said outermost point thereby presenting an inclined surface to receive the flange of the container being operated on by said can opener, and wherein one of said wing portions is secured

5 to the rest of the spring guide member more rigidly than the other of said wing portions.

3. A can opener comprising a cutting element, a container feeding means, and guide means, for positioning the container in the can opener, said guide means comprising a flat metal spring guide member, having lateral forwardly extending wing portions on both sides of said feeding means, each of said wing portions having an outermost point and extending upwardly and inwardly from said outermost point thereby presenting an inclined surface to receive the flange of the container being operated on by said can opener, and wherein one of said wing portions is longer than the other of said wing portions and extends upwardly to a point above the uppermost extent of the other wing portion.
